[57] CLAIM

The ornamental design of an inspection lamp for fluorescence detection in air conditioning systems, as shown and described.

DESCRIPTION

FIG. 1 is a front view of the inspection lamp for fluorescence detection in air conditioning systems, with the broken line showing for illustrative purposes only and forming no part of the claimed;

FIG. 2 is a back view of the inspection lamp for fluorescence detection in air conditioning systems.

FIG. 3 is a top view of the inspection lamp for fluorescence detection in air conditioning systems.

FIG. 4 is a bottom view of the inspection lamp for fluorescence detection in air conditioning systems; and,

FIG. 5 is a side view of the inspection lamp for fluorescence detection in air conditioning systems. The opposite side is identical.
